DESIGN FOR A DRINKING FOUNTAIN UNIT

Sidney A. Whitt, Yonkers, N. Y., assignor to Cordley & Hayes, New York, N. Y., a corporation of New York

Application October 10, 1945, Serial No. 122,719

Term of patent 14 years

(Cl. D91—3)

To all whom it may concern:

Be it known that I, Sidney A. Whitt, a citizen of the United States and a resident of Yonkers, county of Westchester, and State of New York, have invented a new, original, and ornamental Design for a Drinking Fountain Unit, of which the following is a specification, reference being had to the accompanying drawing, forming a part thereof, and wherein

I claim:

The ornamental design for a drinking fountain unit, substantially as shown.

SIDNEY A. WHITT.
